UNITED STATES PATENT OFFICE.

JOSEPH P. SMITH, OF HARTFORD, CONNECTICUT, ASSIGNOR OF ONE-HALF
TO JOHN C. LONG, OF SAME PLACE.

DESIGN FOR A SOCKET FOR WINDOW-FASTENERS.

SPECIFICATION forming part of Design No. 27,468, dated August 3, 1897.

Application filed June 22, 1897. Serial No. 641,840. Term of patent 14 years.

To all whom it may concern:

Be it known that I, JOSEPH P. SMITH, a citizen of the United States, residing at Hartford, in the county of Hartford and State of Connecticut, have invented a certain new and useful Design for Window-Bead-Fastener Sockets, of which the following is a specification.

In the accompanying drawings, which illustrate the invention, Figure 1 shows a plan of a window-bead-fastener socket fashioned according to the design. Fig. 2 shows an edge view, and Fig. 3 shows a diametrical section of the same, these views being deemed necessary to clearly illustrate the design.

The leading features of the design are the rounded or curled rim for the outer edge of the socket with the V-shaped inclining notches in diametrically opposite parts of the side wall and inner edge of the rim.

The socket in plan shows a central circular recess with an oblong opening 1 through the inner wall 2. There is an annular rim or curled flange 3 around the outer edge of the side wall of the socket, and in diametrically opposite parts of this rim or flange and also in the adjacent parts of the side wall there are what appear on looking at the plan to be

V-shaped notches 4. These V-shaped notches are opposite the long sides of the oblong opening through the inner wall, and they increase in width as they extend outwardly toward the rim from the inner wall—that is, these notches increase outwardly from nothing at the inner wall to full width at the rim. 35

Looking edgewise at the socket the side wall has substantially parallel faces with a somewhat curled rim at the outer edge, except where the V-shaped notches are in the side wall and rim, and at these points the side 40 wall of the socket appears to slope outwardly from the inner wall, and this gives the wall of the socket, when looking at it edgewise toward the parts containing the notches, as shown in Fig. 3, the appearance of being tapering or inclining outwardly from the inner 45 wall, although the body of the socket is substantially cylindrical.

I claim as my invention—

The design for a socket for window-bead 50 fasteners herein shown and described.

JOSEPH P. SMITH.
